UNITED STATES PATENT OFFICE.

MAX DORN, OF ST. LOUIS, MISSOURI.

TRANSOM SIDE BEARING.

SPECIFICATION forming part of Letters Patent No. 754,979, dated March 22, 1904.

Application filed May 4, 1903. Serial No. 155,496. (No model.)

To all whom it may concern:

Be it known that I, MAX DORN, a citizen of the United States, residing at the city of St. Louis, State of Missouri, have invented a certain new and useful Improvement in Transom Side Bearings, of which the following is a specification.

My invention relates to a new and useful improvement in transom side bearings, and has for its object to provide a transom side bearing which will be durable and efficient and which may be adjusted to any transom of a car regardless of the angle with the horizontal of that portion of the transom to which the side bearing is attached, and thus save the cost of making patterns for a new transom side bearing every time the angle of this portion of the transom is changed.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 is a plan view of the side bearing attached to a body-bolster or transom. Fig. 2 is a section of the side bearing on the line 2 2, showing the transom in elevation. Fig. 3 is a section of car and truck with side bearing in place. Fig. 4 is a plan view of same with car-floor removed.

1 is the body-bolster or transom of the car. 2 is the truck-bolster of the car and has nothing to do with my invention, but merely shows the relative position of the parts.

3 is the truck side bearing and has nothing to do with my invention, but merely shows the relative position of the parts.

Transom side bearings are usually in one piece; but my invention shows it in two parts. The upper part 4 is fastened to the transom rigidly by means of the bolts 5, which are countersunk into the lower part of the said part 4. The lower surface of part 4 represents an arc

or circular surface, which rests on a corresponding arc-surface, as shown in drawings in part 6, or the lower half of said transom side bearing, which is held in place by being swung or pivoted to part 4 by means of the bolts 7. Thus the lower part of the said transom side bearing is held rigidly in place by the pivotal bolts 7, and thus the side bearing may be adjusted to any transom, whatever the angle of said transom 1 may be, and dispenses with the necessity of providing new patterns every time the angle of the transom is different. The bolts 7 carry no strain; but the strain is taken up on the circular surfaces.

It is not intended, neither is it possible, for the curved surfaces to act as a pivot for the bearing, as all the strains act toward the center of the arc of the curved surface, their only use being to adjust the bearing to fit any transom.

Having thus described the invention, what I claim is—

1. The combination in a transom side bearing of two parts, one above the other, the lower part being attached to the upper part so as to rest rigidly on circular or arc surfaces by means of bolts so as to be adjustable to any transom regardless of the angle with the horizontal of that portion of the transom to which the side bearing is attached, and thus avoid having new patterns made for every transom with different angle.

2. The combination of a transom side bearing in two pieces the lower part being fastened to the upper part so as to rest rigidly on circular or arc surfaces by means of bolts so as to be adjustable to any transom regardless of the angle with the horizontal of that portion of the transom to which the side bearing is attached and means for placing the strain on circular surfaces, all substantially as set forth.

In testimony whereof I have hereunto affixed my signature in the presence of two subscribing witnesses.

MAX DORN.
